UNITED STATES PATENT OFFICE.

FREDERICK JEFFERSON, OF WEST BROMWICH, ENGLAND.

CARBON-SHEET HOLDER.

SPECIFICATION forming part of Letters Patent No. 763,762, dated June 28, 1904.

Application filed October 12, 1903. Serial No. 176,792. (No model.)

To all whom it may concern:

Be it known that I, FREDERICK JEFFERSON, a subject of the King of Great Britain, residing at High street, West Bromwich, England, 5 have invented a certain new or Improved Carbon-Sheet Holder, of which the following is a specification.

My invention consists of the new or improved combined supporting plate or board 10 and carbonic-paper carrier hereinafter described to be used in manifold writing, the said invention having for its principal objects to render unnecessary the handling of the carbonic paper and to obviate the attendant objection thereto—namely, the soiling of the fingers—to facilitate the introduction of the carbonic paper between the pages of the manifold-copy book, and to permit of the simultaneous withdrawal of the writing plate or 15 board and carbonic paper.

By the expression "carbonic paper" I wish it to be understood that I include the various kinds of prepared paper used in manifold writing, some of which are sold under the 25 names "carbonic-ink paper" and "carbon paper."

The essential feature of my invention consists of the addition to or combination with the plate or board employed to give solidity 30 when writing and a rest for the hand of a clip or grip by which one edge of the sheet or sheets of carbonic paper may be held, so that the combined supporting-plate and carbonic-paper carrier may be handled without bringing the fingers into contact with the carbonic 35 paper.

I will describe my invention in connection with the accompanying drawings, of which—

Figure 1 represents in plan the combined 40 supporting-plate and carbonic-paper carrier with the sheet of carbonic paper applied thereto. Fig. 2 is a portion of the same, drawn to a larger scale, without the carbonic paper. Fig. 3 is a section on the line $\alpha\alpha$, 45 Fig. 2; and Fig. 4 is a similar view to Fig. 3, the gripping-bar of the clip or grip in the said Fig. 4 being in its opened or raised position. Figs. 5 and 6 are perspective views 50 illustrating the use of the combined supporting-plate and carbonic-paper carrier.

Referring to Figs. 1 to 6, both inclusive, *a* is the supporting plate or board, having combined therewith (at one side) a clip or grip, the gripping-bar of which is marked *b*. *c* is the sheet of carbonic paper, secured to the 55 plate *a* by the bar *b*. The gripping-bar *b* when in its closed or gripping position, Figs. 1, 2, and 3, occupies a shallow trough *d* near the edge, hereinafter called the "outer" edge of the plate *a*, the upper surface of the bar *b* being flush with the surface of the plate *a*. To increase the effect of the gripping action of the bar *b* on the sheet of carbonic paper *c*, the under surface of the bar *b* and bottom of the trough *d* are corrugated, as is best seen in Figs. 3 and 4. 60 The bar *b* is provided, approximately centrally thereof, with a projection forming a lever *g*, which has its upper face slightly below the plane of the upper face of the gripping-bar *b*. The lever *g* extends through an opening 70 in the plate *a* at that side of the trough *d* which is nearer the outer edge of the plate *a* and is connected to the lower face of said plate by means of a spring-hinge, the joint or hinge-pin of which is denoted by the reference 75 character *e* and the wire springs thereon by *f*. A trough-like piece secured to the lower face of the lever *g* forms a cover for the springs *f* and serves to prevent dust and other 80 foreign matter from gaining access to the springs. The outer edge of the plate *a* has a cut-away portion under which extends the free end of the lever *g*, so that when said free end is depressed the bar *b* is caused to rise 85 from the trough *d*.

The carbonic paper *c* is applied to the supporting-plate *a* by raising the bar *b* by pressure of the thumb on the lever *g* and slipping one of the longitudinal edges of the sheet of carbonic paper *c* under the said bar *b*. On 90 relaxing the pressure of the thumb on the lever *g* the bar *b* closes down on the edge of the carbonic paper *c* and grips it in the trough or depression *d* with such tightness as to render its accidental detachment from the supporting-plate *a* practically impossible. When 95 it is desired to introduce the supporting-plate *a* and carbonic paper *c* into a manifold-copy book, the plate *a* is taken by its outer edge in the right hand and by turning the wrist the 100

said plate *a* is nearly inverted, as is illustrated in Fig. 5. By this action the inner edge of the carbonic paper is caused to leave the plate, as is shown by the said Fig. 5. The manifold-copy book being opened at the desired place, the supporting-plate *a* is introduced therein, the last leaf of a set which are about to be duplicated being allowed to fall or close on the plate. The sheet of carbonic paper *c* is turned onto the leaf on the plate, as is illustrated in Fig. 6, and the leaf or form which is to be written and simultaneously copied is permitted to close on the carbonic paper. To withdraw the supporting-plate *a* and carbonic paper *c*, it is only necessary to take hold of the outer edge of the plate *a* and draw the said plate outward, when the carbonic paper *c* is simultaneously withdrawn.

It is thought that the many advantages of my improved carbon-sheet holder can be readily understood from the foregoing description, taken in connection with the accompanying drawings, and it will, furthermore, be evident that changes, variations, and modifications can be resorted to without departing from the spirit of the invention or sacrificing any of its advantages, and I therefore do not wish to restrict myself to the details of construction hereinbefore described and as shown in the accompanying drawings, but reserve the right to make such changes, variations, and modifications as come properly within the scope of the protection prayed.

Having now described my invention, what I claim as new, and desire to secure by Letters Patent, is—

1. A carbon-sheet holder comprising a base member having a trough at a point removed from one end thereof, an opening at one side of said trough, said trough end of the base having its edge cut away approximately centrally thereof, a gripping-bar for gripping a carbon-sheet in said trough and having a projection extending through said opening and below the lower face of the base and past said cut-away portion, and a spring-hinge attached to the lower face of the base and engaging with said projection for connecting the bar to the base and retaining the bar in close contact with the base, said projection adapted, when its free end is depressed, to cause the gripping-

bar to rise from the trough and thereby release the carbon-sheet from the base member.

2. A carbon-sheet holder, comprising a base member having a trough at a point removed from one end thereof, said trough provided with corrugations, an opening at one side of said trough, said trough end of the base having its edge cut away approximately centrally thereof, a gripping-bar for gripping a carbon-sheet in said trough, said gripping-bar provided on its lower face with corrugations, said gripping-bar further provided with a projection extending through said opening and below the lower face of the base and past said cut-away portion, and a spring-hinge attached to the lower face of the base and engaging with said projection for connecting the bar to the base and retaining the bar in close contact with the base, said projection adapted, when its free end is depressed, to cause the gripping-bar to rise from the trough and thereby release the carbon-sheet from the base member.

3. A carbon-sheet holder, comprising a base member having a trough at a point removed from one end thereof, an opening at one side of said trough, said trough end of the base having its edge cut away approximately centrally thereof, a gripping-bar for gripping a carbon-sheet in said trough and adapted when in its effective relation, to present its upper face approximately in the same plane with the upper face of the base member, said gripping-bar further provided with a projection extending through said opening below the lower face of the base and past said cut-away portion, and a spring-hinge attached to the lower face of the base and engaging with said projection for connecting the bar to the base and retaining the bar in close contact with the base, said projection adapted, when its free end is depressed, to raise the gripping-bar from the trough and thereby release the carbon-sheet from the base member.

In testimony whereof I have hereunto set my hand in presence of two subscribing witnesses.

FRED. JEFFERSON.
